UNITED STATES PATENT OFFICE.

LOUIS MARCEL GABRIEL LOURDIN, OF PARIS, FRANCE.

DIRIGIBLE LIGHT.

1,127,463.

Specification of Letters Patent.

Patented Feb. 9, 1915.

Application filed May 19, 1913. Serial No. 768,629.

To all whom it may concern:

Be it known that I, Louis MARCEL GABRIEL LOURDIN, citizen of the Republic of France, residing at 11 Rue Demours, Paris, France, have invented certain new and useful Improvements in Dirigible Lights, of which the following is a specification, reference being had therein to the accompanying drawing.

10 This invention has for its object certain improvements in the pivoted or jointed head lamp or searchlight carrier which forms the subject matter of my U. S. Letters Patent No. 1,062,833. This head lamp is mounted so as to be able to be operated from a distance, and it enables the beam of light to be projected upward or downward as well as to right or left.

15 In the patent above named an arrangement has been described for causing the lamp to oscillate on its trunnions and about the axis of the supporting fork, comprising toothed pinions mounted on one of the trunnions of the lamp, and on the rod of the 20 supporting fork, the said pinions gearing with chains which are continued by cables surrounded with flexible sheaths and connected with the ends of cruciform arms mounted after the manner of a Cardan 25 joint and operated by a single lever fixed at the intersection of the arms. This arrangement of cruciform arms for operating the cables has the disadvantage of not permitting the cables to have a uniform tension 30 while being operated, and the headlight responds less perfectly to the movements which it is desired to give it.

According to the present invention the 35 cruciform arms are replaced by a combination of pulleys which yield the same result, while however insuring a uniform tension of the cables. Further a solid and compact arrangement is obtained which enables the controlling member to be easily arranged 40 within reach of the driver when the head lamp is employed for motor cars.

Now referring to the accompanying drawings: Figure 1 is a partial front view of the head light, its supporting fork being 45 shown in section; Fig. 2 is a side view of the head light with the lower part of its support in section; Fig. 3 is a plan view of the means for giving the head light a rotation about its vertical axis; Fig. 4 is a 50 view in perspective of the apparatus for

operating the cables; Fig. 5 is a detail mid-sectional view of the means for supporting the operating apparatus shown in Fig. 4.

The head light is indicated by 1 and is mounted on trunnions 2 in a fork 3, the stem 4 of which may pivot in a socket 5 which serves it as support. The arms of the fork and the stem are hollow. A pinion 6 is keyed on one of the trunnions 2 of the head light and the teeth of this pinion engage a chain 7, to the ends 8 of which two cables 9, 10, are attached which pass through the interior of the arm of the fork and its stem and finally end at the operating apparatus shown in Fig. 4. At the lower end of the stem 4 a pinion 11 is keyed, which gears with a chain 12 to the ends of which two cables 14—15 are attached which connect with the operating apparatus shown in Figs. 4 and 5. The whole mechanism of this apparatus is held suspended beneath a suitable support by a rod 16 of square section threaded at its end in order to receive a nut. On this square rod a sleeve 17 which is cylindrical externally is 65 fitted and is secured by the nut on the rod. This sleeve has two arms 18 which form a fork and hold between them a pulley 19 which revolves on an axis 20. The supporting sleeve 17 of this pulley being fixed, this pulley can always only revolve in the same vertical plane.

The external cylindrical part of the sleeve 17 serves as a pivot to a concentric sleeve 21, the two arms of which carry a horizontal 70 pulley 22 of the same diameter as the pulley 19, but as these two pulleys although being of the same diameter must be independent one of the other, they must be eccentric and one must intersect the other. To this end the pulley 22 is slotted at 23 in order to allow the arm of the pulley 19 to pass. When the mounting is completed, the two parts of the pulley 22 may then be brought together and held if necessary by a plate screwed on the 75 inner side of the disk. The cables 9—10 and 14—15, serving for operating the movements of the head light, are fixed on these pulleys. The rotation of these pulleys each in its own plane is produced by a single handle 24 which may control them separately or simultaneously in order to produce displacements of the cables, the resultant of which will give the desired position to the 80 head light. For this purpose the handle 110

24 is connected to the hub 25 of the pulley 19 by a joint 26 in such a way that only the vertical movements of the handle influence the pulley 19, while the lateral movements 5 of the handle cause the rotation in a horizontal plane of the pulley 22. For this purpose this pulley has in addition to these supporting arms a semicircular sector 27 which has a slot 28 into which the rod of the handle 24 fits and which acts as a guide piece for the latter. It is evident that in this way the pulley 22 will follow the handle in all its lateral displacements and in order to allow of these lateral displacements of the 10 handle the pulley 19 is slotted at 29 between the arms of the joint of the handle 24. When the handle is displaced obliquely it simultaneously controls the two pulleys and the resultant of the displacements of the 15 cables will give the head light the desired inclination.

The semi-circular sector 27 along the slot 28 may be provided with notches while the handle has a stud yieldingly mounted which 25 engages the corresponding notch in such a manner that the handle remains fixed in each position. The pulley 22 rotating in a horizontal plane may be fixed in position by a screw 37.

30 In order that the operating cables may always remain taut, they are surrounded with sheaths formed of helically wound metal wires. The sheaths which surround the cables 9 and 10 abut on the one hand 35 against a plate 30 placed in the upper part of the fork a little below the pinion 6. They pass through an oblong aperture 31 formed in the plate 32 and their other end against a regulating nut. The cables 14—15 are 40 also surrounded with sheaths. These latter abut on the one hand against a regulating nut and on the other hand against the plate 32. In case the distance between the head light and the operating lever necessitates a 45 second series of sheaths for the tension of the cables, the latter may be kept taut by a common regulating arrangement or even

each of the latter may be provided with a separate regulating nut.

In the description the means which have 50 appeared to be the most advantageous for putting the invention effectively into practice have been described, but it will be evident that the details of construction are 55 adapted to be modified and that the invention is based on the application of the characteristic arrangements which have been indicated, while these arrangements may be employed separately or in combination.

Having now particularly described and 60 ascertained the nature of my said invention and in what manner the same is to be performed, I declare that what I claim is:

1. A pivoted supporting fork and a light pivotedly mounted thereon; in combination 65 with two pulleys intersecting each other and mounted to revolve on axes at right angles to each other, a handle engaging both of said pulleys and adapted to control either or both at will, and separate cables connected to said pulleys and to said fork and pivoted light respectively, whereby movements of said pulleys are transmitted to said light, substantially as described.

2. In a means for transmitting movements 70 to a light mounted so as to be tiltable on two axes, a fixed mounting, a revoluble pulley carried thereby, a sleeve revolubly carried on said fixed mounting, depending arms on said sleeve, a second pulley carried by said 75 arms having a rim intersecting said first named pulley, a handle fixed to the hub of said first named pulley, means fixed to said second pulley engaging said handle, and cables attached to and extending from said 80 pulleys respectively to said light and operatively connected to said light, substantially as described.

In witness whereof I have hereunto set my hand in the presence of two witnesses.

LOUIS MARCEL GABRIEL LOURDIN.
